CAR DOOR

Gabriel Madland, Chicago, Ill., assignor to The
Youngstown Steel Door Company, Cleveland,
Ohio, a corporation of Ohio

Application September 1, 1936, Serial No. 98,992

16 Claims. (Cl. 20—22)

This invention relates to car doors and is directed to improvements in sliding car doors of the lift type and means for limiting closing movement of said doors and locking thereof in closed position.

The instant improvements are particularly applicable to the auxiliary doors of railway house cars which cooperate with main doors to control openings of extraordinary width provided in the 10 sides of such cars utilized for the shipment of automobiles, furniture and other bulky lading. The auxiliary doors carry posts secured to the front margins thereof and movable with said doors. These posts are presently utilized to limit 15 closing movement of said doors and to secure locking thereof in closed position. In the attainment of these results the posts cooperate with upper and lower stop castings, the latter castings being secured either directly to the side sills of 20 the car underframe or to threshold plates which are bolted to said side sills.

The difficulties which these lower stop castings present are serious. Securement directly to the side sills requires gaining out of the floor boards 25 which lie above the side sills and either coping of the threshold plate or the use of a two piece threshold plate. Such securement moreover requires a variety of stop castings to satisfy variation in the construction and placement of side 30 sills. Securement to the threshold plate is unsatisfactory since subsequent warping and shrinkage of the floor boards renders them ineffective as a solid backing for the threshold plates. When the lower stop castings are struck by trucks or 35 the like in the loading or unloading of a car, loosening of the threshold plates occurs. Since the lower stop castings are fastened to the threshold plates their position is disturbed and hence their cooperation with the door posts for 40 the stated purpose is lost.

Most serious of the difficulties encountered is found in the projection of the lower stop castings above the floors of the cars. They thus impair loading and unloading of cars and have frequently caused damage to automobiles and other 45 lading handled by means of dollies or the like. When these dollies accidentally strike the projecting stop castings they are caused to swing about and the automobile on the dolly to strike 50 against the car with resulting damage to said automobile.

The main objects of this invention are therefore to provide a lower stop member cooperable with a sliding lift door to stop opening movement of and secure locking engagement with said

door; to provide a lower locking member which may embody a stop for sliding lift doors, said member terminating below the door opening; to provide a lower locking member for such doors which may be secured to the door track and made 5 a standard design; to provide a lower locking member which shall serve to properly guide such doors in their final closing movement and resist outward pressure of the lading against said doors; and to provide sliding lift doors embodying gusset members formed with locking detents cooperable with lower locking members having any or all of the characteristics set out above.

Other objects of the invention will become clear as the description thereof proceeds. 15

For the attainment of these objects the instant invention comprises the novel structure and combination of parts hereinafter described and particularly pointed out and defined in the appended claims. 20

In the drawings forming a part of this specification:

Figure 1 is a partial elevation of a railway house car embodying the instant invention.

Figure 2 is a horizontal section taken on line 25 2—2 of Figure 1.

Figure 3 is a vertical section taken on line 3—3 of Figure 1.

Figure 4 is a vertical section taken on line 4—4 of Figure 1. 30

Figure 5 is a detail of a lower corner of a sliding lift door in locking relationship with the embodiment of the invention illustrated in Figure 1 on an enlarged scale.

Figure 6 is a vertical section taken on line 6—6 35 of Figure 7.

Figure 7 is a view similar to Figure 5 showing a modified form of the invention.

Figure 8 is a horizontal section taken on line 8—8 of Figure 7. 40

Figure 9 is a detailed view of another form of the invention showing the securement thereof to a door track which is illustrated in section.

Referring to the drawings and more particularly to the embodiment of the invention illustrated in Figures 1 to 5 inclusive, the numeral 10 designates as a whole the portion of the railway house car illustrated. Each side of the house car is provided with a door opening of extraordinary width, such as indicated at 11 in Figure 2 50 of the drawings. Each door opening is defined by means of the door posts 12 and 13, and by means of a side plate 14 connecting these posts at the top, and a side sill 15 connecting the door posts at the bottom. 55

To close the door opening 11 a pair of oppositely sliding doors is utilized. The right hand, or main door 16, comprises a metallic panel 17 provided with a plurality of spaced horizontal corrugations 18 and vertical corrugations 19 and 20 adjacent the edges of the metallic panel and into which the horizontal corrugations merge. The forward vertical margin of the door 16 is reinforced by means of a substantially channel shaped member 21 which as hereinafter pointed out serves as a weatherproofing member as well. The rear vertical margin of the door is reinforced by means of a buffer angle 22 and a sealing strip 23 secured to said margin of the door as by means of a vertical row of rivets 24. The sealing strip 23 is adapted to cooperate with a guard strip 25 secured to the post 13 in the closed position of the main door in order to seal said margin of the door. The upper horizontal margin of the door 16 is reinforced by means of an angle 26 having a vertically disposed leg secured to said margin of the door and a horizontally disposed leg extending inwardly for the purpose hereinafter set forth in the description of the other or auxiliary door. The lower horizontal margin of the main door is reinforced by means of an angle member 27, more particularly described in the consideration of the auxiliary door.

The auxiliary door 28 comprises a metallic panel 29 formed with a plurality of spaced horizontal corrugations 30 which merge at their ends into vertical corrugations 31 and 32 formed adjacent the edges of the metallic panel. The forward vertical margin of the auxiliary door is reinforced by means of a substantially Z shaped member 33 which serves as a stop for the main door 16 and which cooperates with the reinforcing channel 21 of the main door in order to seal the meeting edges of the main and auxiliary doors as best illustrated in Figure 2 of the drawings.

An additional reinforcing post 34 substantially Z shaped in section is fastened to the forward vertical margin of the auxiliary door, this post 45 being braced by means of a knee brace 35 secured to said post as by the rivets 36 and to the panel of the door as by the rivets 37. Reinforcement of the rear vertical margin of the auxiliary door is provided by the buffer angle 22 and sealing strip 23 secured to said margin as by means of rivets 24. The sealing strip 23 cooperates with the guard strip 25 secured to the door post 12 for the purpose hereinbefore indicated. A reinforcing member 26 is secured to the upper horizontal margin of the auxiliary door, this securing being effected by means of a row of horizontal rivets 38 passing through the vertically disposed leg 39 of the reinforcing angle. The horizontally disposed leg 40 of said angle extends inwardly in overlapping relationship with a substantially J shaped header 41 which is secured to the depending leg 42 of the side plate 14. The upper margin of the auxiliary door and the main door as well, is overlapped by means of a retaining bar 43 secured to the depending leg 42 of the side plate 14 as by means of rivets 44 in order to prevent accidental disengagement of the upper portion of these doors from the car. A reinforcing angle 27 is secured to the lower horizontal margin of the door by means of rivets 45 extending through the vertically disposed leg 46 of said reinforcing member. The horizontal leg 47 of said angle member 27 extends horizontally outwardly and is adapted to have frictional engagement with the inwardly extending hor-

izontal leg 48 of an angular track 49 for a purpose which will hereinafter appear.

As best shown in Figure 4 of the drawings, the reinforcing post 34 terminates above the floor 50 of the car. A threshold plate 51 fastened to the side sill 15 by means of bolts 52 is utilized to protect the outer portion of the floor.

In the closed position of the main and auxiliary doors they are adapted to be locked together by means of a locking mechanism indicated generally by the reference numeral 53. Opening and closing mechanism for the doors is shown as a whole at 54.

Both the main and auxiliary doors are of the sliding lift type. Doors of this type are characterized by the fact that in their normal or lowered position they are frictionally supported upon a track, or the like, and in their elevated position the support is transferred to antifriction means whereby the doors may readily be moved along the track in order to control the door opening. As far as the instant invention is concerned any type of lifting mechanism may be utilized for the doors. One form of such mechanism is illustrated generally in Figure 1 of the drawings and comprises briefly brackets 55 and 56 secured respectively adjacent the lower corners of the doors. The bracket member 55 carries a roller housing 57 which is journaled in said bracket. A roller 58 is carried by the roller housing 57, the axis of rotation of said roller being offset relative to the journal of the roller housing.

The bracket 56 similarly carries a roller housing 59 provided with a roller 60. The roller housings 57 and 59 are connected by a bar 61 so that the operation of these housings will be simultaneous. An operating lever 62 mounted upon one of the journals of the roller housing 59 is utilized to impart rotating movement of the roller housings about the rollers as fulcrums in order to obtain a lifting movement of the door. The lifting mechanism hereinabove described is well known and its operation well understood in the art. Inasmuch as the lifting mechanism utilized for the main door is the same as that hereinabove described, no particular reference to the lifting mechanism of the main door will be made.

When the doors are in their normal or lowered position frictional engagement between the horizontal flange 47 of the angular reinforcing member 46 and the horizontal leg 48 of the track 49 is established. In order to move the doors upon the rollers of the lift mechanism the operating lever 62 is pulled downwardly whereupon the doors will be elevated upon the rollers, which may then readily move upon the track. When the doors reach their closed position the levers are released whereupon the door gravitates downwardly to again establish frictional engagement with the angular reinforcing member 46 of the door track. The above described lifting and lowering movement of the doors is utilized particularly in the instance of the auxiliary door to secure automatic locking engagement of said door while at the same time fulfilling all of the objects hereinbefore enumerated.

To this end in the embodiment illustrated in Figures 1 to 5 inclusive, a locking member 63, preferably in the form of a casting, is secured to the track 49 as by means of rivets 64 passing through said member and the depending vertical leg 65 of the track. The rivets 64 are utilized additionally to fasten a member 66 to said track for a purpose which will be hereinafter described.

The locking member 63 is provided with an

upwardly extending locking projection 67 which, as clearly appears in Figures 4 and 5 of the drawings, terminates below the door opening. In order to render the locking projection 67 effective 5 as a means for locking the auxiliary door in its closed and lowered position, said projection extends through an opening 68 formed in the door track 49 and through an opening 69 formed in the horizontal flange 47 of the angular reinforcing member 46.

It will be apparent from the foregoing that the locking member 63 is disposed below the track and within the vertical depending flange thereof so as to be protected by the track.

15 The auxiliary door adjacent its forward lower corner is provided with a locking detent adapted for cooperation with the locking projection 67 in order to lock the door. For this purpose, in the considered embodiment of the invention, a 20 channel shaped member 70 is secured to the forward vertical margin of the door. This securing is effected by means of rivets 71 passing through the web 72 of the member 70 and through the door. The channel member 70 is disposed so that the flanges 73 and 74 thereof extend outwardly. With particular reference to Figure 5 of the drawings it will be seen that the web 72 and the flange 73 of the member 70 terminate above the flange 74 as indicated at 75. The 25 flange 74 is bent inwardly to provide an extension 76 which is disposed upon the horizontal flange 47 of the angular reinforcing member 46. The extension 76 terminates at the opening provided in the horizontal flange 47. Said flange 30 together with the extension 76 thereby constitutes a locking detent adapted to be associated in locking relationship with the projection 67 formed on the member 64 as clearly shown in Figure 5 of the drawings.

40 Assuming the door to be in open position a lowering movement of the operating lever 62 will effect an elevating movement of the auxiliary door. The amount of elevation of the door provided by the lifting mechanism is such that the horizontal flange 47 of the reinforcing member 46 may assume a position above the top of the locking projection 67. In this position the door may be moved upon the rollers of the lifting mechanism to closed position where upon 45 release of the operating lever 62 the door will move downwardly and the locking detent on the door will automatically assume locking relationship with the locking projection 67.

In the event however, that the door is not 50 sufficiently elevated so that the horizontal flange 47 will clear the locking projection, said flange will strike against the projection as the door is moved to its closed position. The locking projection, therefore, is tapered as indicated at 55 77 and when this tapered portion is struck by the flange 47 it will cause the door to elevate sufficiently to ride over the locking projection 67.

As best illustrated in Figure 2 of the drawings, the auxiliary door when in its closed position is disposed behind the member 66 secured to the vertical depending leg 65 of the door track. Said member is provided with a generally convex inner face 78 which serves to guide the door in its final closing movement. The 60 said member moreover cooperates with the channel member 70 in order to resist outward pressure of the lading against the door. This channel member 70 is secured by means of the rivets 71 to the reinforcing post 34 thereby utilizing the strength of this post to resist outward pres-

sure against the lower forward corner of the door.

Since the instant invention is confined to means for locking the lower portion of a sliding lift door, the means for locking the upper portion of such door as employed at the present time is adhered to. This latter means embodies briefly a stop and locking casting 78A fastened to the depending vertical flange 42 of the side plate 14. This casting is provided with locking 10 abutments 79 and 80 with which locking detents 81 and 82 provided on a casting 83 secured to the upper portion of the post 34 as by means of rivets 84 cooperate.

In Figure 9 of the drawings a modified form 15 of the invention hereinabove considered is illustrated. In this form the separate locking member 63 and guide and retaining member 66 are formed integrally as shown at 85. The member 85, preferably in the form of a casting, is provided with a locking projection or abutment 86, which is adapted to extend upwardly through the opening 68 formed in the horizontal leg 48 of the track 49. The depending leg 65 of the track lies between the two branches 87 and 88 20 of the substantially U shaped casting 85. Rivets 89 serve to fasten the member 85 to this depending leg of the track. The outer branch 88 of the member 85 projects above the track and the projecting portion 90 serves to guide the 25 door in its final closing movement and to cooperate therewith to resist outward thrusts upon the door.

The form of the invention illustrated in Figures 6 to 8 inclusive, incorporates in addition 30 to the automatic locking features hereinabove considered, means which cooperate to limit the closing movement of the door. In addition the form of the invention illustrated in Figures 6 to 8 inclusive, makes possible the elimination of 35 the openings in the door track and in the angular reinforcing member 46.

The considered embodiment of the invention utilizes a member 91 preferably in the form of a casting secured to the vertical depending leg 45 65 of the track as by means of rivets 92. The casting 91 is suitably reinforced by means of the spaced ribs 93, 94, and 95. The reinforcing rib 93 terminates substantially at the horizontal leg 48 of the track. The connecting web 96, 50 which extends between the reinforcing ribs 93 and 94, is spaced below the upper part of the reinforcing rib 93. The vertical reinforcing ribs 94 and 95 and the connecting portion 97 of the casting extend upwardly above the track 49, 55 but terminate below the door opening 11. By virtue of the hereinabove described construction of the casting 91 the reinforcing rib 93 serves as a locking abutment and the reinforcing rib 94 serves as a stop for the door as hereinafter 60 described. Moreover, the connecting portion 97 of the bracket which lies above the track and which is provided with a convex inner face 98 serves to guide the door in its final closing movement and to cooperate therewith to resist outward pressure against the door.

The door which is the auxiliary door is substantially of the same construction as the auxiliary door 28 hereinabove described. However in place of the channel member 70 there is utilized a gusset member 99, preferably in the form of a casting, and secured to the forward vertical margin of the door as by means of rivets 100 and to the adjacent lower horizontal margin 70 of the door as by means of rivets 101. The up- 75

per rivets 100, moreover, secure the gusset member 99 to the reinforcing post 34. The gusset member 99 carries a stop and locking detent 102. This stop and locking detent, as clearly shown in Figure 8 of the drawings, projects outwardly from the door in substantially horizontal alignment with the reinforcing rib 94. In the closed and lowered position of the door the locking detent 102 is disposed in the recess provided by the vertical reinforcing ribs 93 and 94 and the connecting portion 96 of the casting 91 which lies between the ribs. This association is clearly illustrated in Figure 7 of the drawings.

Assuming the door to be in its open position it may readily be moved to closed position, as hereinabove described. As the door approaches its closed position it will be guided by the inner convex face 98 of the casting 91. Since the door is elevated during the closing movement the locking detent 102 provided on the gusset member 99 will be elevated above the reinforcing rib 93. As the door reaches its closed position the locking detent 102 will engage the reinforcing rib 94 and thereby the closing movement of the door will be arrested. Upon release of the operating lever 62 of the lifting mechanism the door will automatically lower, thus establishing locking engagement between the locking detent 102 and the vertical rib 93 which then functions as a locking abutment.

Manifestly, numerous changes and modifications in the details of the embodiments of the invention disclosed will become apparent to those skilled in the art. It is intended that all such changes and modifications be comprehended within the scope of the invention which is to be limited only by the claims appended hereto.

I claim:

1. In a railway house car having a door opening and a track secured to said car below said opening, a member secured to said track having a locking abutment disposed below said door opening, a lift door for said opening adapted for sliding movement upon said track, a locking detent provided on said door, said detent being associated in locking relationship with said locking abutment by lowering movement of said door for the purpose set forth.

2. In a railway house car having a door opening and a track secured to said car below said opening, a member secured to said track, a lift door for said opening adapted for sliding movement upon said track, means on said member and said door cooperable in the elevated position of said door for limiting closing movement thereof and cooperable means on said member and said door associated by lowering movement of said door to prevent opening movement thereof, said latter means on said member being disposed below said door opening.

3. In a railway house car having a door opening and a track secured to said car below said opening, a member secured to said track having a locking abutment disposed above said track and terminating below said door opening, a lift door for said opening adapted for sliding movement upon said track, a locking detent provided on said door, said detent being associated in locking relationship with said locking abutment by lowering movement of said door for the purpose set forth.

4. A door for railway house cars comprising elevating mechanism for imparting vertical movement to said door and for supporting said door for sliding movement upon said car, a reinforcing post secured to the forward margin of

and terminating above the lower edge of said door, a gusset member secured to the lower forward corner of said door, means securing said gusset member to said reinforcing post and a locking detent on said gusset member for the purpose set forth.

5. A door for railway house cars comprising elevating mechanism secured to the lower margin thereof for imparting vertical movement to said door and supporting said door for sliding movement upon said car, a gusset member secured to the lower forward corner of said door and a locking detent provided on said gusset member, said detent being adapted for locking cooperation with a locking abutment on said car by lowering movement of said door and for release from said abutment by elevating movement of said door.

6. In a railway house car having a door opening, a track secured to said car below said opening, a member secured to said track having a locking abutment projecting upwardly through said track and terminating below said door opening, a lift door for said opening adapted for sliding movement upon said track, said door having a locking detent disposed in locking engagement with said abutment by lowering movement of said door for the purpose set forth.

7. In a railway house car having a door opening, a track secured to said car below said opening, a member secured to said track having a locking abutment projecting upwardly through said track and terminating below said door opening, a lift door for said opening adapted for sliding movement upon said track, an angular reinforcing member secured to the lower margin of said door having a horizontal flange adapted to have frictional engagement with said track in the lowered position of said door, said horizontal flange having an opening therein through which said locking abutment projects in the closed and lowered position of said door for the purpose set forth.

8. In a railway house car having a door opening, a track secured to said car below said opening, a member secured to said track having a locking abutment projecting upwardly through said track and terminating below said door opening, a lift door for said opening adapted for sliding movement upon said track, an angular reinforcing member secured to the lower margin of said door having a horizontal flange adapted to have frictional engagement with said track in the lowered position of said door, said horizontal flange having an opening therein, a gusset member secured to the lower forward corner of said door, said gusset member having a flange disposed upon said horizontal flange and terminating adjacent one edge of said opening in said horizontal flange, said locking abutment projection through said opening in said horizontal flange of the reinforcing member in the closed and lowered position of said door, said horizontal flange adjacent said opening and said flange on said gusset member cooperating with said locking abutment for the purpose set forth.

9. In a railway house car having a door opening, a track secured to said car below said opening, a member secured to said track having a locking abutment projecting upwardly through said track and terminating below said door opening, a lift door for said opening adapted for sliding movement upon said track, said door having a locking detent disposed in locking engagement with said abutment by lowering movement of said door, said member having a portion extend-

ing above said track for cooperation with the lower forward portion of said door to guide said door in the final closing movement thereof and to resist outward pressure against said door when the latter is in closed position.

5 10. In a railway house car having a door opening and a track secured to said car below said opening, a member secured to said track having a locking abutment and a stop abutment disposed below said door opening, a lift door for said opening adapted for sliding movement upon said track and means on said door, said means engaging said stop abutment when said door is elevated to limit closing movement thereof and assuming locking relationship with said locking abutment when said door is lowered in closed position.

11. In a railway house car having a door opening and a track secured to said car below said opening, a member secured to said track having spaced locking and stop abutments disposed below said door opening, a lift door for said opening adapted for sliding movement upon said track, a gusset member secured to the lower forward corner of said door, a locking detent on said gusset member, said detent engaging said stop abutment in the elevated position of said door to limit closing movement thereof and establishing locking relationship with said locking abutment when 30 said door is lowered in closed position.

12. In a railway house car having a door opening and a track secured to said car below said opening, a member secured to said track having a locking abutment and a spaced door guide and retaining member, a lift door for said opening adapted for sliding movement upon said track, a gusset member secured to the lower forward corner of said door, a locking detent on said gusset member, said detent engaging said guide and retaining member in the elevated position of said door to limit closing movement thereof and establishing locking engagement with said locking abutment when said door is lowered in closed position, said guide and retaining member guiding the forward portion of said door in the final closing movement thereof and resisting outward pressure against said door in the closed position thereof.

13. In a railway house car having a door opening, a track secured to said car below said door

opening and oppositely sliding main and auxiliary doors of the lift type supported upon said track for closing said door opening, said auxiliary door having a post secured to the forward margin thereof and extending inwardly of said car, stop and locking abutments secured to said track and disposed below said door opening, reinforcing means secured to the outside of said auxiliary door substantially at the lower forward corner thereof, said means comprising a locking detent, 10 said detent engaging said stop abutment in the elevated position of said door to limit closing movement thereof and establishing locking relationship with said locking abutment in the closed and lowered position of said door.

15 14. In a railway house car having a door opening and a track secured to said car below said opening, stop and locking abutments secured to said track and disposed below said door opening, a lift door for said opening adapted for sliding movement upon said track and means on said door, said means engaging said stop abutment when said door is elevated to limit closing movement thereof and assuming locking relationship with said locking abutment when said door is lowered in closed position.

15 20 15. In a railway house car having a door opening, a track secured to said car below said opening, a member secured to said track, a lift door for said opening adapted for sliding movement 30 upon said track, means on said member and said door cooperable in the elevated position of said door for limiting closing movement thereof and cooperable means on said door and said member associated by lowering movement of said door to 35 prevent opening movement thereof, said latter means on said member being disposed below said door opening.

16. In a railway house car having a door opening, a track secured to said car below said opening, a member secured to said track having a locking abutment disposed above said track and terminating below said door opening, a lift door for said opening adapted for sliding movement upon said track, a locking detent provided on said door, 40 said detent being associated in locking relationship with said abutment by lowering movement of said door to prevent opening movement thereof.

GABRIEL MADLAND. 50
